UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed April 28, 1926. Serial No. 105,101.

This invention relates principally to metal car roofs of the flexible single course type, wherein the roof sheets are independently movably supported between carlines on the 5 side plates of the car and on purlins that are secured to the carlines and extend longitudinally of the car between carlines.

The principal object of the present invention is to reduce the cost of roofs of the 10 above type, to simplify the construction thereof and to facilitate the operation of assembling the roof.

The invention consists principally in an arrangement that supports the side marginal portions of the sheets at intervals throughout their length and renders the unsupported middle portions of the sheets strong enough to support the vertical roof load. The invention further consists in the 20 parts and in the arrangements and combinations of parts hereinafter described and claimed.

In the accompanying drawing which forms part of this specification and wherein 25 like symbols refer to like parts wherever they occur,

Fig. 1 is a plan view of a portion of the car roof embodying my invention,

Fig. 2 is an enlarged transverse section 30 through one-half of the roof on the line 2-2 in Fig. 1,

Fig. 3 is a longitudinal section through the roof on the line 3-3 in Fig. 1, and

Figs. 4 and 5 are vertical longitudinal sections, similar to Fig. 3, showing modified forms of the invention.

Referring to Figs. 1 to 3, inclusive of the accompanying drawing, my invention is shown in connection with a car roof comprising 40 Z-bar side plates 6 connected by carlines 7 of inverted channel-shaped section having lateral base flanges 8 resting on and rigidly secured to the top flanges of said side-plates. Roof sheets 9 extend from side 45 to side of the car between carlines with their eaves end portions resting on filler blocks 10 secured to the tops of the side plates. The roof sheets are narrower than the spaces between carlines and are provided with depending eaves flanges 11 that overhang the outer edges of blocks 10 and are spaced therefrom, whereby said sheets are independently movable.

The roof sheets are provided with up-

standing side marginal flanges 12 that are straddled by seam caps or covers 13 of substantially inverted channel-shaped section that have lateral base flanges 14 that rest on the body portions of the sheets inside of the side marginal flanges thereof. The seam covers 13 rest on and are riveted to the flat tops of the carlines 7 and are provided at their eaves ends with depending flanges 18 that overhang and are spaced from the eaves corners of adjacent sheets.

Running boards 15 extend longitudinally of the car at the ridge and are supported on and secured to the lateral top flanges of Z-shaped running board saddles 16 whose lateral base flanges rest on the ridge portions 70 of the seam covers and are secured in position by the rivets that secure the ridge portions of said seam covers to the carlines.

Sheet supporting members 20 are rigidly secured to the base flanges of the carlines by 75 means of bolts 21. The supporting members are disposed transverse or crosswise to the length of the carlines and project on opposite sides of said carlines and are spaced apart longitudinally thereof. As shown in 80 the drawing, said supporting members are secured to the carlines at the ridge of the car and at points substantially midway between the ridge and eaves thereof. The supporting members of adjacent carlines are 85 opposed to and terminate short of each other, but project far enough beyond the sides of the carlines to support the side marginal portions of the sheets while permitting slight sluing movement thereof. The 90 sheets are provided with upstanding corrugations or stiffening ribs 22 that are located in line with and overlap the ends of the supporting blocks of adjacent carlines.

By the arrangement described the portions 95 of the supporting blocks that project beyond the sides of the carlines function after the manner of cantilever arms which support the side marginal portions of the sheets and cut down the effective span that the sheets 100 have to bridge; while the corrugations or ribs formed in the sheets span the spaces between the opposing ends of the cantilever arms of adjacent carlines and thus serve to increase the vertical strength of the unsupported portions of the sheets and render them strong enough to support the vertical 105 roof load.

The above described roof construction is simple and it can be very easily assembled and repaired; and it greatly reduces the cost of the roof by dispensing with the use 5 of purlins and by substituting therefor sheet supports comprising a multiplicity of short and inexpensive pieces of lumber that can be easily handled and readily secured in place.

10 In the modification of the invention shown in Fig. 4, the sheets are stiffened between the supporting members of adjacent carlines by means of stiffening ribs or corrugations 22^a that extend transversely of the 15 car parallel to the carlines.

In the modification shown in Fig. 5, the sheets 9^a are stiffened between the supports 20^a of adjacent carlines by arching the body portion over the spaces between said supports, whose projecting portions have their upper surface curved to correspond to the radius of curvature of the arched body portion of said sheets.

Other modifications of the form and arrangement of the parts may be made in view of the foregoing description of the invention; and the invention is not restricted to the forms and arrangements shown in the drawing.

30 What I claim is:

1. A car roof comprising side plates, carlines supported thereby, metal roof sheets, supports for said roof sheets, said supports being mounted on said carlines and extending 35 transversely of said carlines beyond the sides thereof, the supports on one carline terminating short of the supports on the next carline, and means for stiffening said sheets between the supports on adjacent carlines, said stiffening means extending between the supports of adjacent carlines and overlapping the ends thereof.

2. A car roof comprising side plates, carlines connecting said side plates, and metal 45 roof sheets, said carlines being provided with a plurality of spaced sheet supporting portions extending beyond the sides thereof, the sheet supporting portions of adjacent carlines being spaced apart longitudinally of the car, said roof sheets being provided with stiffening ribs that span the spaces between the sheet supporting portions of adjacent carlines and overlap the ends of said portions.

3. A car roof comprising side plates, carlines supported by said side plates, metal roof sheets, and supports for said sheets, said supports being secured to said carlines and extending on opposite sides thereof, the supports of adjacent carlines being spaced apart 60 longitudinally of the car and the portions of the sheets located between the supports of adjacent carlines being provided with stiffening ribs that extend from a support 65 on one carline to a support on an adjacent

carline and overlap the ends of said supports.

4. A car roof comprising side plates, carlines connecting said side plates, metal roof sheets arranged in the spaces between carlines, seam covers covering the carlines and the marginal portions of adjacent sheets, and a plurality of sheet supports secured to the carlines crosswise to their length, the supports on one carline terminating short of the supports on the next carline, the portions of the sheets located between the ends of the supporting members of adjacent carlines being provided with stiffening ribs.

5. A car roof comprising side plates, carlines connecting said side plates, metal roof sheets arranged in the spaces between carlines, seam covers covering the carlines and the marginal portions of adjacent sheets, and a plurality of sheet supporting members secured to the carlines crosswise to their length, the supports on one carline terminating short of the supports on the next carline, the portions of the sheets located between the ends of the supporting members of adjacent carlines being provided with stiffening ribs that extend from the supporting members on one carline to the supporting member on an adjacent carline.

6. A car roof comprising side plates, carlines connecting said side plates, metal roof sheets arranged in the spaces between carlines, seam covers spanning said carlines and the adjacent side marginal portions of said sheets, and a plurality of supports for said roof sheets, said supports being secured to said carlines crosswise to their length, the supports of adjacent carlines being opposed to and terminating short of each other, said sheets being formed with stiffening ribs that extend between the opposed supports on adjacent carlines.

7. A car roof comprising side plates, carlines connecting said side plates, spaced sheet supports secured to said carlines crosswise to their length and projecting on opposite sides thereof in alignment longitudinally of the car, and roof sheets resting on the projecting portions of the supporting members of adjacent carlines and spanning the spaces therebetween, said roof sheets being provided with stiffening corrugations that extend from the support on one carline to the support on an adjacent carline.

8. A car roof comprising side plates, carlines connecting said side plates, said carlines being provided with a plurality of spaced arms that project laterally therefrom on opposite sides thereof, and roof sheets arranged between adjacent carlines with their side marginal portions resting on the lateral arms thereof, said arms extending far enough inside the side lines of said sheet to constitute cantilever arms for supporting the side marginal portions of said sheets.

9. A car roof comprising side plates, carlines connecting said side plates, said side plates being provided with a plurality of arms that project laterally therefrom on opposite sides thereof, and roof sheets arranged with their side marginal portions resting on the lateral arms of said carlines, said arms constituting cantilevers for supporting the side marginal portions of said

sheets, said sheets being provided with ribs 10 that are disposed in line with and overlap the ends of the cantilever arms of adjacent carlines and thus serve to increase the load carrying capacity of said sheets.

Signed at New Kensington, Pennsylvania, 15 this 23rd day of April, 1926.

CHARLES DAVID BONSALL.
